UNITED STATES PATENT OFFICE.

GEORGE E. HOMER, OF BOSTON, MASSACHUSETTS.

DESIGN FOR A SPOON.

SPECIFICATION forming part of Design No. 23,379, dated June 19, 1894.

Application filed January 25, 1894. Serial No. 498,064. Term of patent 7 years.

To all whom it may concern:

Be it known that I, GEORGE E. HOMER, of Boston, in the county of Suffolk and State of Massachusetts, have invented and produced

15 a new and original Design for Spoons, of which the following is a specification, reference being had to the accompanying drawing, which shows the essential features thereof.

The drawing represents a front elevation 10 of a spoon showing my design.

The leading feature of my design consists in a raised surface at the end portion of the handle showing an egg shell, broken and a chicken partially out of the same, as it ap-

15 pears at the last stage of incubation, or hatch-

ing and a twisted handle with the ornament connecting the same with the bowl. The handle connecting with the smaller end of

20 the egg, and extending nearly to the bowl,

20 represents a twisted cord, which connects with a double leaf, or scroll leaves having in-

ward edges raised and scalloped, and the end portions of which curve outwardly, and meet the broad rounded inward end portion of the bowl, in outline.

25

In the drawing hereto annexed and to which reference is made, A represents the bowl of the spoon and joining the rear portion of the bowl is an ornament B, joining the lower end of the twisted cord handle C, 30 to the upward end of which connects the smaller end of the egg shell E, having a chicken F, breaking therefrom, its head projecting slightly above the broken large end of the shell as shown.

35

Having thus described my design, I claim—

The design for a spoon as herein shown and described.

GEORGE E. HOMER.
